UNITED STATES PATENT OFFICE.

CLAUDE M. GARLAND, OF CHICAGO, ILLINOIS.

BOILER CLEANER.

1,416,552.

Specification of Letters Patent. Patented May 16, 1922.

Original application filed February 7, 1916, Serial No. 76,611. Renewed July 14, 1920, Serial No. 396,330. Divided and this application filed May 8, 1919, Serial No. 295,659.

To all whom it may concern:

Be it known that I, CLAUDE M. GARLAND, a citizen of the United States of America, residing at Chicago, in the county of Cook and State of Illinois, have invented certain new and useful Improvements in Boiler Cleaners, of which the following is a specification, reference being had therein to the accompanying drawings.

10 The invention relates to the art of cleaning boilers and similar apparatus, and it is the object of the invention to more effectively remove the soot or other deposits from the heating surface to maintain a higher degree of efficiency during operation.

At the present time soot blowers are used for this purpose and consist of steam or air nozzles adapted to discharge a jet of steam or air upon the surfaces to be cleaned.

20 These nozzles are commonly connected to branch lines which connect with a header so that steam may be admitted to different points by opening a valve placed in the branch between the header and the nozzle.

25 These valves as now used are operated by hand. Common practice is to admit steam through each branch for a period of about five minutes two or three times a day.

The object of all soot blowers is to remove 30 the accumulation of solid matter which deposits from the gases upon the tubes, thereby increasing the resistance to heat flow from the gases to the medium within the tubes and thereby decreasing the efficiency

35 of the heating process. When a soot blower is used intermittently as above described the solid matter which deposits during the eight or ten hours between the periods of blowing has time to bake on the tube and is there-

40 fore much more difficult to remove and ordinarily cannot all be removed by the blowing process, but must be scraped off. Furthermore I have found by experiment in the case of water tube boilers that the soot which

45 deposits on the outside of the tubes in a period of two hours is sufficient in many cases to decrease the efficiency of the boiler over three per cent. For example in a cer-

50 tain boiler the temperature of the flue gases when operating under uniform conditions immediately after blowing the tubes was 450° F. Two hours after blowing, due to the accumulation of soot on the external wall of the tubes, the temperature had risen to

525° F., thus increasing the loss due to inefficient soot blowing over three per cent.

The present invention overcomes the above described difficulties by substituting for the occasional or irregular blowing a periodic blowing at regular intervals. Furthermore 60 instead of long continued blowing the interval during which the steam or other blowing medium is discharged is relatively short. Thus instead of the removal of thick deposits of soot the boiler surface is maintained 65 relatively clean at all times, while the amount of steam required for the cleaning is no greater than that which would be necessary for the occasional cleaning. The invention therefore consists in the novel 70 process or method of cleaning as hereinafter set forth.

My improved method may be carried out in various types of apparatus, but I shall specifically describe one construction, which 75 is illustrated in the drawings, in which

Figure 1 is a side elevation and Figure 2 is a plan view of a water tube boiler to which my soot blower apparatus has been attached;

Figure 3 is a cross-section; 80

Figures 4 and 5 are respectively an elevation and cross-section of the controlling switch;

Figure 6 is a diagram of the electrical apparatus; 85

Figure 7 is a cross-section; and

Figure 8 is a side elevation of a modified form of apparatus.

In these figures like numerals refer to like parts. 3 indicates the drums of the 90 boiler, 2 the rear header and 2' the front header, in which the tubes 1 are expanded in the ordinary manner. 6 indicates the side walls while 7 indicates the furnace and 5 the outlet for the flue gases. 8 are the 95 baffles which direct the gases through the tubes 1. 4 is the nozzle for the discharge of steam from the boilers. 9 is a steam main supplied with steam under boiler pressure which is connected at some point 100 to the steam distribution system about the plant. 12, 12' and 12² are branch pipes from the main 9. 10, 10' and 10² are quick opening steam valves of the solenoid type in which the valve is held on its seat by 105 a spring and which is lifted against the force of the spring through a solenoid when an electric circuit is closed. When the

2

circuit is broken the spring again seats the valve. The valves are common to the art and require no further description. To the branches 12, 12' and 12² are connected 5 the nozzle pipes 16 through the elbows 13 and the stuffing boxes 14. 17 are nozzles in the pipes 16 which are adapted to discharge steam into the bank of tubes 1. The nozzle pipes 16 have sprocket wheels 15 10 rigidly attached to them. The nozzle pipes 16 are supported rotatably in the stuffing boxes 14 and in the bearings 34, the latter being mounted in the side wall 6.

The nozzle pipes 16 are rotated by the 15 sprockets 15 which are driven by the chains 11, which are in turn driven by the sprockets 18 rigidly mounted on the shaft 19, which is mounted in the bearings 20 and adapted to be rotated continuously by a 20 variable speed motor 23 which is mounted on the wall 21 and drives through the gears 22.

On the shaft 19 are rigidly mounted contact arms 25, 25' and 25², an enlarged section of one of these is shown in Figure 5. The contact arms are provided with contact pieces slidably mounted and held against the contact plates 24, 24' and 24² by springs 27. On the wall 21 are mounted 30 brackets 29 which support the contact plates 24, 24' and 24² about the shaft 19 and adjacent the contact arms 25, 25' and 25². The contact plates consist of the insulating disks 40 which are preferably of slate or 35 hard rubber which are bolted to the brackets 29 by the bolts 30. In the disks 40 are imbedded the metal strips 31 carrying the contact points a', b', c', d', e', f', g', and h'. The strips 31 are bolted to the 40 disks 40 by the bolts 38. 35 is a nut which holds the connection 36 to the electric circuit in place. When the shaft 19 revolves the contact piece 26 travels over the contact 45 points a', b', c', etc., but does not come in contact with the strip 31. Figure 2 shows a plan view of the assembled shaft, contact plates, etc. The Figure 4 shows a front view of a contact plate which are all identical and Figure 3 shows an enlarged section through the branch 12.

Figure 6 is a wiring diagram showing the connections for operating the solenoid valves 10, 10' and 10² through the contact plates 24, 24' and 24² through the contact 55 arms 25, 25' and 25². By the closing of the switch 43 connection is made with a source of electrical energy which passes along one side of the circuit 42 and connects through the lines 46, 46' and 46² to the 60 shaft 19. The lines 46, 46' and 46² are shown to complete the diagrammatic arrangement, as only one connection to the shaft is necessary, the shaft 19 and the three contact arms form one and the same 65 circuit. The side of the circuit 41 connects

to the solenoids 10, 10' and 10² and passes through these to the lines 44, 44' and 44² respectively. These lines connect to the strip 31 of the contact plates 24, 24' and 24² respectively. The shaft 19 rotates in 70 a counter clockwise direction and as the arm 25 touches the contact point a' on the contact plate 24 the electric circuit is closed and the solenoid 10 lifts the valve off of its seat, and as the arm 25 passes off of the 75 contact point a' on its way to b' the circuit is broken and the valve seats itself by the action of the spring, not shown. The contact arm 25' is set a little behind the contact arm 25 so that the solenoid 10' operates a few seconds after the solenoid 10 is 80 operated. The arm 25² is set a little behind the arm 25' so that the solenoid 10² operates a few seconds after the solenoid 10'. This arrangement is used so that the branch 85 12 will blow first, and before the soot has time to settle itself on the tubes 1, blown by the branch 12, the solenoid 10' operates to blow the tubes covered by 12', and before the soot from the tubes covered by 12 and 90 12' has time to settle on the tubes covered by 12² the solenoid 10² operates to blow these tubes and the soot from all the tubes passes out through the uptake 5 with the 95 flue gases.

Eight contact points a', b', c', etc., are arranged on each contact plate 24, 24' and 24² and these contact points are arranged so that for each revolution of the nozzle pipes 16 each branch 12, 12' and 12² blows in eight 100 different positions marked a, b, c, d, e, f, g and h on Figure 1. By this arrangement it will be seen that all portions of the tubes are carefully blown and that the dust from the front end of the tubes does not have an 105 opportunity to settle on the rear portion of the tubes.

The contact arms 25 are adjustably mounted on the shaft 19 so that they may be adjusted to cause the branches 12, 12' and 12² to 110 blow in any given order of succession or all of them to blow simultaneously. A variable speed motor 23 is used to drive the shaft 19 so that any desired time interval may be obtained between the blows. For the purpose 115 of regulating the time of the blow, that is the actual length of time that the solenoids hold the valves open, the contact pieces 26 are varied in width, also the contact points a', b', etc. If very short quick puffs are desired, the contact piece 26 would be about $\frac{1}{16}$ of an inch thick while the contact points a', b', etc., would be of like width. If a longer period of blow were desired contact pieces 120 26 $\frac{1}{2}$ of an inch wide which would double 125 the period of blow, or contact pieces $\frac{1}{4}$ of an inch wide which would quadruple the time of the blow could be used.

Figure 8 shows a side elevation of a water tube boiler which is provided with a soot 130

blower of the stationary type in which the nozzles discharge parallel to the tubes instead of at an angle to the tubes as shown in Figure 1. My device can be equally well applied to this system of soot blowing. The steam is admitted through the main 9 and the solenoid operated valves 10, 10' and 10² are placed in the branches 12, 12' and 12². In this arrangement the nozzle pipes 16 are provided with nozzles 17 which are located between the tubes 1, as shown in Figure 7, which is a part section on the line 7—7 looking toward the branch 12. The shaft 19 rotates the arms 25, 25' and 25² which make the contacts, thereby operating the solenoids 10, 10' and 10² as previously set forth.

In order to make it possible to blow the tubes in the case of an accident to the motor or shafting switches 45, 45' and 45² are provided for closing the circuits to the solenoids 10, 10' and 10². During normal operation the switches 45, 45' and 45² remain open. From the above description it will be seen that I have provided novel means for continuous removal of soot from heating surfaces. It should be understood that this specification and the accompanying drawings show typical arrangements of my apparatus. My apparatus and my improvements can be applied to any soot blowing system of the type described. It is immaterial as to the type of a boiler, the number of branches necessary or the arrangement of the branches. It is further immaterial as to the

type of quick opening valve used. This may be a valve operated through a mechanical trip or operated by a hydraulic or steam cylinder. I prefer, however, the solenoid operated type. It also would not be considered a departure from the intent of my improvements to place a quick opening valve in the main 9 and discharge through this valve to one or more branches.

What I claim as my invention is:—

1. The method of cleaning boilers and similar apparatus which consists in automatically periodically blowing the surface thereof, and in automatically quickly opening and closing the discharge to produce puffs of relatively short duration. 50

2. The method of cleaning boiler parts of the accumulation of soot and like products of combustion, while preventing substantial decrease in the efficiency of the boiler between the periods of cleaning, which consists in determining the period in which the accumulation of soot deposits on the boiler parts will become materially deleterious to the efficiency of the boiler by incrustation on such parts, and then causing the delivery 60 of a blast of steam over the boiler parts to be cleaned to forcibly remove the soot therefrom, and insuring that the delivery of the blast shall be at fixed and regular intervals less than that required for such deleterious 65 accumulation to take place.

In testimony whereof I affix my signature.
CLAUDE M. GARLAND.
